(57) **CLAIM**

The ornamental design for a generator cover, as shown and described.

DESCRIPTION

FIG. 1 is a first perspective view of a generator cover showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the generator cover thereof;

FIG. 10 is a perspective view of another state of the generator cover thereof;

FIG. 11 is a perspective view of another state of the generator cover thereof;

FIG. 12 is a perspective view of another state of the generator cover thereof;

FIG. 13 is an enlarged view of the selected portion 13 in FIG. 1; and,

FIG. 14 is an enlarged view of the selected portion 14 in FIG. 1.

The broken lines shown in the drawings depict portions of the generator cover that form no part of the claimed design.
